Des. 219,926

Patented Feb. 16, 1971

219,926

FARROWING PEN

Lyle W. Lage, Gladbrook, Iowa 50635

Filed Sept. 22, 1969, Ser. No. 19,248

Term of patent 7 years

Int. Cl. D30—01

U.S. Cl. D30—1

Fig. 1

Fig. 2

Fig. 3

Fig. 4

Fig. 5

FIG. 1 is a front elevational view of a farrowing pen showing my new design.

FIG. 2 is a rear elevational view thereof.

FIG. 3 is a side elevational view thereof as seen from the left-hand side of FIG. 1;

FIG. 4 is a side elevational view thereof as viewed from the right-hand side of FIG. 1; and

FIG. 5 is a plan view thereof.

I claim:

The ornamental design for a farrowing pen, substantially as shown.
